UNITED STATES PATENT OFFICE.

DAVID BUCKLER, ROBERT D. CAIN, JULIUS TAUBERT, AND EDWARD N. PELZER, OF IONIA, MICHIGAN.

BUGGY-BOOT.

SPECIFICATION forming part of Letters Patent No. 322,518, dated July 21, 1885.

Application filed September 24, 1884. (No model.)

To all whom it may concern:

Be it known that we, DAVID BUCKLER, a subject of Great Britain, and ROBERT D. CAIN, JULIUS TAUBERT, and EDWARD N. PELZER, 5 citizens of the United States, residing at Ionia, in the county of Ionia and State of Michigan, have invented a new and useful Improvement in Boots for Buggies and the like, of which the following is a specification, reference being had to the accompanying drawings.

This invention relates to boots for buggies and the like; and it has for its object to provide a device of this character which will be simple and durable in construction, convenient in application, and efficient in use; which will conform to the shape of the body, but not inclose its edges, and which will be provided with means for automatically locking the boot in its closed position.

20 With these and other objects in view the said invention consists in certain details of construction and combination of parts, as hereinafter set forth, and particularly pointed out in the claims.

25 In the accompanying drawings, Figure 1 is a perspective view of a buggy-body with our improved boot applied thereto, and showing it in the raised position. Fig. 2 is a longitudinal sectional view of the same. Fig. 3 is a 30 detail view of the frame to which the boot is attached. Fig. 4 is a detached transverse section on the line *x x*, Fig. 2.

Like letters are used to indicate corresponding parts in the several figures.

35 Referring to the drawings, A designates a buggy-body of the ordinary construction, which we have shown in order to give a clear idea of the nature of the present invention.

B designates a frame, which may be made 40 of wood, metal, or any suitable material, and preferably rectangular in form, consisting of sides *a a* and ends *b b*, the forward portions of the sides being bent or inclined upward at *c c'*, the end *b* being attached or formed with the 45 extremity of the inclined portion. We have shown the frame as made in one piece of material; but of course we do not wish to be limited to this construction. As will be seen, the bending or inclining of the sides enables the 50 frame to conform to and rest against the rear end of the seat-frame, and thus allow the at-

attachment of the boot to the under side of the seat, as will be presently explained.

To each of the sides *a* of the frame are attached spring-catches *C C*, which are in the 55 form of a compound curve, their lower ends being turned inward to form a bearing-point, *d*, above the ends.

D designates the boot, made of leather and fitting over the frame, the edges of the boot 60 fitting around and inclosing the sides *a* and ends *b*, and stitched to the boot within the frame, as seen at *e*. The front end of the boot is extended beyond the frame *B* at *E*, and attached to the under side of the seat *F* by 65 means of buttons, rivets, or other suitable means, this attachment forming what might be called a hinge, the boot turning on this point when raised or lowered.

The operation of our invention will be readily understood from the foregoing description, taken in connection with the annexed drawings. The spring-catches are attached to the frame, the boot secured thereto, and also attached to the under side of the seat. In its 75 closed position the leather-covered frame rests on the upper edge of the body, but does not inclose its edges, as formerly, so as to hide or disfigure the outlines of the body. When closed down, the bearing edge or point *d* of the 80 catches *C* bears against the inner side of the body and holds the boot in that position.

In raising the boot the catches will automatically yield by reason of their peculiar construction, and in closing down the bearing-edge *d* will abut against the inner side of the body, yield outward, and then spring back into position. In this manner the boot may be raised and lowered at will and in a very short time, since there are no buttons, hooks, 85 or eyes or similar fastenings to release.

The rigid frame serves as a support for the boot proper to retain it in shape, so as to prevent sagging in the middle.

The boot and the supporting-frame are to 95 be made to conform to the shape of the body, and may be detached therefrom at will. We do not limit ourselves to any particular form, material, or construction, as such may be varied at will and come within the scope of the 100 present invention. The boot is simple and durable in construction, it presents a neat and

tasteful appearance, and will prove of utility and benefit for the purposes intended.

Having described our invention, we claim—

- 5 1. A boot for buggies and the like attached to a rigid frame or support, which rests on the upper edges of the body, and spring-catches depending from the support or frame and automatically locking and releasing the boot, as set forth.
- 10 2. The combination, with the body, of the boot attached to a rigid frame or support, which is hinged substantially as described, and spring-catches depending from the support or frame

and having their bearing-edges pressing against the inner face of the sides of the body, 15 as and for the purpose set forth.

In testimony that we claim the foregoing as our own we have hereto affixed our signatures in presence of two witnesses.

DAVID BUCKLER.
ROBERT D. CAIN.
JULIUS TAUBERT.
EDWARD N. PELZER.
